CLAIM

The ornamental design for an outer covering for earbud case, as shown and described.

DESCRIPTION

FIG. 1 is a front perspective view of an outer covering for earbud case according to a first embodiment of our design; FIG. 2 is a bottom rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines shown in the drawings are for the purpose of illustrating environmental structure that forms no part of the claimed design.
